METHOD AND APPARATUS FOR FORMING A CLOTH SELVAGE

Richard D. Wood, Jr., Wawa, Pa., and George Thomson, Milton, and Carl F. Whitaker, Beverly, Mass., assignors to Millville Manufacturing Company, Millville, N. J., a corporation of New Jersey

Application June 27, 1952, Serial No. 297,736

32 Claims. (Cl. 154—1.8)

This invention relates in general to improved methods and apparatus for cutting textile cloth sheet material and at the same time securing the cut fiber ends so as to provide one or more selvages at the points of cutting. The term "selvage" as hereinafter employed in the specification is intended to define and include sheet material woven or otherwise and having one or more edges extending longitudinally or transversely thereof, which edges are so formed as to prevent ravelling, roughening, or fraying.

The conventional procedure of sewing or stitching hems along the cut edge of the sheet material ordinarily involves separate handling operations which add to the cost of certain types of specialty cloth items, such as diapers, towels, mechanics' wipe-up cloths, and the like, especially where it is desired to cut off lengths of cloth from a web of sheet material in a continuous operation.

To avoid stitching, many proposals have been made for securing together the folded portions of a hem by means of an adhesive type binder employed either as a coating or impregnating agent, or utilized in the form of fusible fibers interwoven with the strands of the material itself. None of these proposals have proved to be a practical solution to the problem, due both to the objectionable characteristics which are imparted to the cloth hem, and to the difficulties in devising a mechanism for continuously carrying out periodic cutting, impregnating, and bonding steps in a satisfactory manner.

The present invention is concerned with the problems indicated in connection with forming selvages, especially those problems surrounding such operations as cutting and securing a cloth hem with an adhesive type binder, and the invention aims to devise improved methods and apparatus for continuously forming selvages along cloth edges of both straight and curved shape. It is also an object of the invention to devise a mechanism for rapidly and cheaply carrying out a novel sequence of operations in connection with a cloth hemming operation. Another object of the invention is to provide a mechanism capable of rapidly and efficiently forming a cloth hem which is of sufficiently rugged construction to undergo a great deal of hard usage, such as is encountered in repeated exposure and washings in chemical reagents, and which is, moreover, capable of retaining a great deal of its normal textile characteristics. Still another object of the invention is to devise a method of handling hemmed cloth to facilitate folding and inspection operations.

These and other objects and novel features will be more fully understood and appreciated from the following description of preferred embodiments of the invention selected for purposes of illustration and shown in the accompanying drawings, in which

Fig. 1 is a view in side elevation of an apparatus for handling a web or roll of cloth from which specialty cloth items are cut off and provided with one or more selvages and subsequently carried away on a conveyor member;

Fig. 2 is a plan view of the selvage-forming apparatus shown in Fig. 1;

Fig. 3 is a diagrammatic view indicating a number of

2

operations carried out in the cloth hemming machine and illustrating particularly the timing relationship of the operations with respect to one another;

Fig. 4 is a diagrammatic view showing parts of the cloth hemming machine and illustrating the position of these parts at the beginning of the cycle of operation, generally indicated in Fig. 3;

Fig. 5 is a diagrammatic view, similar to Fig. 4, and illustrating a succeeding step in the cycle of operation referred to and in which a cutting member is moved into an advanced position;

Fig. 6 is a diagrammatic view similar to Figs. 4 and 5 and illustrating still another step in which a former element is moved into cooperative relationship with the cutting member;

Fig. 7 is a diagrammatic view similar to Figs. 4 to 6, inclusive, but showing the former element moved out of engagement with the cutting member to leave folded cloth portions surrounding the cutting member;

Fig. 8 is a similar diagrammatic view showing the cutting member in a retracted position corresponding to the position shown in Fig. 4, and further indicating respective positions assumed by the textile material;

Fig. 9 is an enlarged fragmentary vertical cross-section through the former element and cutting member in a position such as that shown in Fig. 6, and particularly illustrating the position of these elements in forming a length of cloth into two connected folds;

Fig. 10 is a view similar to Fig. 9 but further illustrating the cutting member advanced beyond its cutting station and also showing a pair of seam setting blocks engaging the folds of cloth with the blade lying therebetween;

Fig. 11 is a fragmentary perspective view of a textile material formed with a hemmed edge by the method illustrated in Figs. 1 to 10, inclusive;

Fig. 12 is an end elevational view of the hemming machine shown in Figs. 1 and 2;

Fig. 13 is an enlarged fragmentary side elevational view of parts of the mechanism shown in Fig. 1;

Fig. 14 is a vertical cross-section taken on the line 14—14 of Fig. 12;

Fig. 15 is an enlarged fragmentary plan view of that portion of the hemming machine included within the bracket A in Fig. 2;

Fig. 16 is an enlarged plan view of parts of the hemming machine included within the bracket B in Fig. 2;

Fig. 16a is a detail plan view showing parts of the bracket supporting means for the former element;

Fig. 17 is an enlarged elevational view of portions of the hemming machine included in the bracket C in Fig. 15;

Fig. 18 is a cross-sectional view taken on the line 18—18 of Fig. 17;

Fig. 19 is a cross-sectional view taken on the line 19—19 of Fig. 17;

Fig. 20 is an enlarged fragmentary plan view of certain parts of the hemming machine included within the bracket D in Fig. 2;

Fig. 21 is a detail cross-sectional view taken on the line 21—21 of Fig. 20;

Fig. 23 is a detail cross-sectional view taken on the line 23—23 of Fig. 20;

Fig. 24 is a plan view of the fold forming element;

Fig. 25 is a cross-sectional view taken on the line 25—25 of Fig. 24;

Fig. 26 is a cross-sectional view taken on the line 26—26 of Fig. 24;

Fig. 27 is a cross-sectional view taken on the line 27—27 of Fig. 25;

Fig. 28 is a front elevational view of a heated seam setting block;

Fig. 29 is a cross-sectional view taken on the line 29—29 of Fig. 28;

Fig. 30 is a detail cross-sectional view of the seam setting block on a somewhat larger scale;

Fig. 31 is an elevational view of a cam member for controlling the feeding of both cloth and adhesive into the machine;

Fig. 32 is an edge view of the cam shown in Fig. 31;

Fig. 33 is an edge view of the cam shown in Fig. 31 but viewed from the opposite side thereof;

Fig. 34 is an elevational view of a cam member for controlling movement of the forming element, seam setting blocks and cutting blade;

Fig. 35 is an edge view of the cam shown in Fig. 34;

Fig. 36 is an elevational view of the cam shown in Fig. 34 but viewed from the opposite side thereof;

Fig. 37 is a fragmentary plan view illustrating mechanism for driving the respective parts of the cloth hemming machine;

Fig. 38 is a plan view illustrating apparatus for receiving and turning hemmed articles with the hemmed portions occurring in an uppermost position;

Fig. 39 is an elevational view further illustrating the structure shown in Fig. 38;

Figs. 40 to 44, inclusive, are sectional and perspective views illustrating a series of steps and modified forms of the apparatus of the invention for producing a cloth item with a selvage of an unhemmed type;

Fig. 45 is a plan view illustrating diagrammatically the handling of a plurality of spaced-apart webs in the machine of the invention; and

Fig. 46 is a diagrammatic view illustrating the feeding of a plurality of cloth webs.

The apparatus illustrated in the figures described and the method which is followed in making use of this apparatus will first be described with reference to cutting off a cloth item and forming a selvage of the hemmed type wherein a cut edge of fabric is turned over upon itself and secured by means of an adhesive type binder. It should be understood, however, that we may desire to carry out forming operations independently of hems.

In producing a hemmed cloth, we have found that it is important to employ a specialized form of binder which is suitable for application to a fabric surface in a controlled manner, and we have discovered that a relatively thin paste-like substance comprising a vinyl copolymer occurring in the form of an organosol, when specially modified with a correctly chosen filler, plasticizer, and swelling agent, may constitute an unusually satisfactory binder material.

The key to success in using an organosol as a satisfactory hem binder we find is largely dependent upon the fact that sharply controlled distribution of swollen organosol particles in the folded hem portions can be realized. It has been determined that since the swollen particles fuse together more easily than normally unswollen binder particles, it is practical to utilize a relatively thinner, more easily dispersed suspension. This type of organosol suspension in practical testing has been found to produce not only an adequate bonding after fusion but also a very desirable degree of pliability in the hem, whereas to obtain a similar bonding effect, with certain other fluid binders, it has been found necessary to use more plasticizer. Increased amounts of plasticizer make the hem heavier, and larger amounts of plasticizer are also subject to migrating difficulties as well as discoloring disadvantages.

We have further found that in utilizing a specialized form of binder, such as the one described above, we may very beneficially control the form and method of application of the binder so that it occurs in the shape of a relatively thin ribbon-like body extending longitudinally along the cloth hem and occurring in spaced relation to the outer border of the hem along its line of folding, with the result that there is formed a tubular margin.

We have further discovered that if we thus provide at the outer border of the hem a tubular margin which is substantially free from binder, this tubular margin compensates for loss of pliability and drape at the adhesively secured portions, and substantially reduces any tendency for the hem to develop objectionable stiffness. It appears from repeated testing and use of the hemmed cloth that the tubular margin at its unsecured parts actually constitutes a soft, yieldable, rolled edge, and it is this soft rolled edge extending along the ribbon-like body of binder which helps to maintain, to an important extent, a desirable degree of pliability and drape in the hem.

Moreover, the rolled edge will normally tend to be of a slightly greater thickness than the binder-held portions of the hem so that the ribbon-like body is not only completely hidden from sight or contact, but is actually disposed in a somewhat recessed or sunken position. It is pointed out that a ribbon-like body of binder in a position such as described will have little, if any, tendency to produce an edge of harsh binding, cutting, or abrasive characteristics.

In addition, we have found that the ribbon-like body of adhesive binder may be desirably controlled in another aspect. We find that if the binder is first brought into contact with the base portion of the hem, i. e., that portion of the sheet material adjacent to the folded portion, there may result a substantially greater concentration and impregnation of the ribbon-like body at and just below the surface of the base portion described.

There is thus produced a desirable anchoring base with which the free folded edge of the hem, including its cut ends, may be brought into register and in which the cut ends may be impressed and solidly embedded. In this way a maximum degree of bonding is achieved with little, if any, spreading of the adhesive binder beyond the cut edge of the folded hem portion taking place.

Moreover, we find that we are able to control the extent to which a binder, such as an organosol, strikes into the fibers of the hem portions and we can very definitely limit impregnation so that we preserve at the exposed fiber surfaces of the hem a great deal, if not all, of the normal textile characteristics of the sheet material.

As illustrative of one cloth item which the apparatus of the invention may deal with, reference is had to producing, preferably from a continuous web of cotton textile material, pieces of hemmed cloth which are to be utilized as diapers. It is pointed out that with an article of this character it is especially essential for the textile characteristics of the hem to be carefully maintained in a condition such that when brought into contact with the skin of an infant there will be no more tendency for irritation and chafing to develop than would be the case of an ordinary cotton textile material. This is so because the hemmed edge of a diaper is usually pinned either about the waist or the legs of an infant and any increase in stiffness, thickness, or loss of pliability in the hemmed portion of the diaper may tend to result in an undesirable impression and a line of chafing or binding of a highly objectionable nature.

The problem is further complicated in the case of diapers by the fact that such articles are frequently retained in a soiled condition for periods of time in closed containers during which time considerable ammonia develops due to bacterial action. The hemmed portion of the diaper must be capable of undergoing alternate wetting and washings involving both mechanical working exposure to ammonia and various other chemical reagents, occurring in soaps and soap-like materials. Also, from a practical standpoint it should be understood that any binder which is to be used may be required to be colorless and capable of resisting any yellowing or change in color in use.

With the foregoing requirements in mind we have devised specific organosol type formulations for use in

diapers and in which are compounded, with particles of the vinyl copolymer organosol resins, carefully selected amounts of filler, plasticizer, swelling agent and diluents which we have found will satisfy the conditions to an extent not heretofore realized, as far as we are aware, particularly when the material is combined with hem sections in the manner hereinafter disclosed. These formulations have been described and claimed in a co-pending application Ser. No. 268,372, filed January 26, 1952.

As illustrative of specific formulations of vinyl copolymer organosols from which adhesive type binders for diaper hems may be obtained, and which are suitable for use with the machine of the present invention, there are cited the following examples:

EXAMPLE I

	Parts
Vinyl chloride acetate	70
Resin-coated precipitate calcium carbonate	27
Titanium dioxide	10
Resinous polyester plasticizer	135
Petroleum thinner	31
Xylol	18
2.1 to 3.5 parts of non-toxic polymeric tin compound.	

EXAMPLE II

	Parts
Vinyl chloride acetate	100
Butyl phthalyl butyl glycolate	80
Resin-coated precipitate calcium carbonate	30
Titanium dioxide	15
Petroleum thinner	54
Xylol	36
3 to 5 parts of non-toxic polymeric tin compound.	35

EXAMPLE III

	Parts
Vinyl chloride acetate	67
Resin-coated precipitate calcium carbonate	27
Titanium dioxide	7.5
Resinous polyester plasticizer	97
Petroleum thinner	31
Xylol	18
2.0 to 3.4 parts non-toxic polymeric tin compound.	45

In order to accomplish a continuous controlled application of adhesive along the lines indicated above, we have devised a novel cloth feeding and selvage-forming apparatus. The selvage-forming apparatus has been especially designed to handle and dispense a fluid adhesive of the general viscosity characteristics exhibited by the examples noted. We have further constructed certain parts of the apparatus with a unique form such that we can simultaneously shape and cut two hemmed sections and in so doing we are enabled to apply adhesive internally of each hemmed section. We thus control the degree of impregnation so that most of the impregnating body occurs between the folds of the respective sections and only small amounts, if any, of the adhesive body are forced through the fabric to undesirably affect the textile characteristics of the fabric at the exposed surfaces of the impregnated portions. At the same time we have devised a structure for dispensing the adhesive in a selective manner so that it occurs on the cloth as a thin ribbon-like body lying in spaced relation to the lines of folding of the hemmed sections and in this way there is produced the desirable tubular margins noted above.

Cloth feeding means

Considering first in detail the cloth feeding mechanism, numerals 2 and 4 denote opposite vertical sides of a machine frame which is supported on feet 6, as

illustrated in Figs. 1 and 2. Mounted at the left-hand end of the frame, as viewed in Fig. 1, is a roll stand including a pair of brackets 8 which project outwardly to support a roll of cloth 10 on roller bearings 12 and 14.

As illustrative of specific formulations of vinyl copolymer organosols from which adhesive type binders for diaper hems may be obtained, and which are suitable for use with the machine of the present invention, there are cited the following examples:

10   Supported at the upper edges of the frame sides 2 and 4 is a table 16 also shown in Fig. 12 over which a web or length of cloth is guided, as suggested by the dotted line showing in Fig. 1. In passing to the table the cloth is first guided around a roller 18 whose opposite ends are carried in two take-off arm members 20 and 22 pivotally mounted on a shaft 24, as shown in Fig. 1. From the roller 18 the cloth travels upwardly and over a guide roll 26 at the upper side of the roll stand, then under a tension bar 28, and then alternately over and under a series of ripple rods 30.

15   Located at the end of the table 16 in a position to receive cloth passing therefrom is a measuring roll 32 mounted on a shaft Q supported between the frame sides 2 and 4. The roll occurs in a position below the front end of the table 16 so that cloth must pass around a part of the outer periphery of the roll along a downwardly extending path.

20   Adjustably secured in rolling contact with the measuring roll 32 is an idler roll 34 on a shaft 36 which is rotatably mounted in slides 38. Slotted brackets 40 support the slides 38 and the slides may be adjusted by means of set screws, as 42, to force the roll 34 against measuring roll 32, as desired.

25   The idler roll 34 and the measuring roll 32, operate to feed a length of cloth therebetween and to support the cloth in a downwardly extending position where it is suspended between two vertical guide plates 80 and 82, and as shown in Fig. 14. The idler roll 34 is preferably provided with a conventional overrunning clutch device 84 (Fig. 16) which prevents the idler from reversing when the take-off arm operates.

30   The measuring roll 32 is actuated intermittently by means of the power driven mechanism shown in Figs. 12, 13, 15, 16 and 37. Included therein is an electrical motor 44 which drives a pulley 46. The latter pulley is belted to a second pulley 48 which operates a gear reducer 50 having a pinion gear A attached to its output shaft. In mesh with pinion A is a gear B fixed on a shaft R which has one extremity received in a bearing in the frame side 4 and the other extremity journaled in the side 2 and extending therethrough to support a gear J, Fig. 12. In mesh with the gear J is a large gear K which is fixed on the outer end of a main cam shaft T journaled in the frame sides 2 and 4, as shown in Figs. 12 and 37.

35   Arranged to be driven by gear K is another gear L which, as shown in Figs. 13 and 15, is mounted to revolve about a shaft U also supported between the frame sides 2 and 4 at points directly above the main cam shaft T. At the opposite end of the shaft U is mounted a gear L' shown in dotted lines in Fig. 13 and also indicated at the bottom of Fig. 2. The gear L' meshes with a gear M carried in a change gear bracket N adjustably secured on the shaft Q. Gear M is arranged to mesh with and drive a gear O fast on shaft Q and in this way there is provided rotative movement of the measuring roll 32 when shaft U is revolved. It will be observed that by means of the change gear arrangement the arc of rotation of the measuring roll 32 may be varied to furnish a range of sizes of textile material which is fed through the roll 32 and idler roll 34.

40   In order to produce rotative movement of shaft U by gear L, the latter gear is operatively connected to the shaft U through a single revolution clutch mechanism so that the gear L', and hence the measuring roll 32, will turn for short intervals interrupted by non-driving periods occurring during each revolution of the main cam shaft T. This clutch mechanism is shown more clearly in Fig. 17, and includes an annular sleeve 52 which is rotatable on the shaft U and keyed to gear L. This sleeve has an

enlarged annular section which is located closely adjacent to a clutch disk 54 having a latch 56. The clutch disk 54 is fixed to shaft U. When the disk through its latch mechanism is engaged with the enlarged annular section of the sleeve 52, the clutch disk and shaft U are driven from rotation of the gear L. To release the latch 56 there is provided a spring-held trip arm 58 pivotally mounted on a stud 60 bolted to the side of the machine frame 2. Cooperating with the spring-held trip arm 58 is a cam member 62 fixed on an outer extending end of the cam shaft T and cam 62 is provided with a cam roll 64 which at one point during rotation of the cam 62 will engage against the trip arm 58 and pivot it outwardly to release the latch 56.

Also provided is a locking cam device for locking the shaft U in precisely the same starting position after each rotative movement. This locking cam arrangement includes a second spring-held arm 66 also pivoted on the stud 60 and operated by a disk 68 on shaft T. A roller 70 on disk 68 is adapted to engage against arm 66 and move it outwardly to release a hooked end 71 which at one point is held in resilient engagement with a slotted portion of a locking cam plate 72. Roller 70 is of a substantially greater diameter than roller 64 to provide for disengaging the locking arm 66 in correct sequence with operation of the latch 56.

It will readily be seen that by means of the single clutch revolution mechanism described a length of cloth of some desired dimension will be caused to be drawn forwardly over the measuring roll and dropped into a suspended position between the guide plates. This operation takes place during a part only of the period in which the main cam shaft T is turning to complete one full revolution.

As an aid to visualizing the timing of the cloth feed relative to rotation of the main cam shaft T, there has been shown diagrammatically in Fig. 3 a timing chart divided into 10° divisions for the full 360° revolution of the cam shaft T. The beginning of the cloth feeding step, which is indicated at the upper left-hand side of Fig. 3, occurs prior to all other movements in the machine, as will readily be apparent from an inspection of the chart, and as all of the other operations about to be described are controlled by the main cam shaft T, the relative sequence of operations subsequent to the cloth feeding, or concurrently with it, are clearly set out.

In continually feeding successive lengths of cloth through the feeding mechanism above described, it may also be desirable to provide a mechanism for unwinding cloth from the roll 10, and as one suitable means of accomplishing this we have further provided a cam controlled linkage for actuating the take-off arms 20 and 22, earlier referred to and shown in Figs. 1 and 12. A bell crank lever 90 causes the take-off arms 20 and 22 to pivot about the shaft 24 when actuated by a link 92 operatively connected to take-off arms 94 and 96 pivotally supported on shaft Z.

The take-off arms are guided by means of a cam follower 98 engaging in cam groove 95 formed in the side of a cam member 100 fixed on the main cam shaft T. One cam face with groove 95 is more clearly illustrated in Figs. 31 and 32. Rotation of the cam 100 causes the take-off arms 20 and 22 to be swung through an arc into the dotted line position shown in Fig. 1, and in so doing to unwind a predetermined length of cloth, after which the cloth is fed to the measuring roll in the manner above described. The cam 100, as shown in Fig. 31 is intended to be illustrative of two of such cams comprising right and left cams both on the same shaft to control the respective take-off cam arms 94 and 96.

If desired, only one take-off cam arm and one cam may be employed.

Selvage forming

Considering next the selvage forming mechanism of the invention, we have devised means for engaging intermediate portions of a length of textile material at two

opposite sides thereof, while in the suspended position described above, and simultaneously forming two separated selvages in a manner which, so far as we are aware, has not been accomplished in other hemming methods.

- 5 Included in the novel means referred to are a reciprocating former element and a movable cutter member which cooperates with the former element to reversely fold sections of the cloth and cut along a transverse line of cutting so that two separate hemmed portions are left. 10 There is also provided an adhesive dispensing apparatus operating through the former, together with special seam setting blocks for applying heat and pressure in the manner about to be described.

These parts will be considered in detail in the order

- 15 in which they operate, as shown on the timing chart of Fig. 3. The sequence of movements of the various parts is also indicated schematically in Figs. 4 to 10, inclusive. The cutter member which operates first after the beginning of the cloth feeding cycle, as indicated in Fig. 3, 20 has been generally indicated by the numeral 110 and comprises a cutter blade or knife solidly mounted in a blade holder 112, better shown in Figs. 14 and 20, which holder is transversely disposed between opposite sides 2 and 4 of the machine, being guided by upper and lower 25 brackets 114 and 116.

Secured at opposite ends of the blade holder 112 are arms, as 118 and 120, which extend rearwardly in the manner illustrated in Fig. 20, and which are pivotally attached to square section toggle members, as 122, also 30 connected to links 124, better shown in Figs. 21 and 22. The links 124 have their inner ends pinned to respective cam arms 126 which are fixed on shaft W.

- The arms 126 are provided with a series of adjustment holes 129, as noted in Fig. 21, to vary the position of the 35 connecting links 124 in the heads of the cam arms 126 and in so doing to vary the travel of the knife 110. At one side of each of the arms 126 are cam followers 128 adapted to be received in cam grooves, as 130, formed in cams 132, as is better shown in Figs. 34 and 35. The 40 cams 132 are mounted on shaft T and are formed as respective right and left-hand members, as will be apparent from an inspection of Fig. 37.

- Attention is directed to Fig. 3 and also to Fig. 34 wherein it will be seen that the cam track or groove 130 is formed to act through its corresponding cam follower and cam arm to move the knife in and out, in accordance with a time cycle which has been illustrated in Fig. 3. As will be noted in this figure, the second graph line shows the knife beginning to start an inward movement at approximately the point at which the cloth feeding mechanism has progressed half-way through its movement, or at the 60° point on the chart.

- 55 During the remaining feeding interval of cloth from the 60° point to the 120° point on the chart, the knife continues to move inwardly and then comes to rest for a dwell occurring between the 120° point and the 200° point. At this point the edge of the knife is approximately in register with the guide plate 82. Cutting takes place during this interval, as will be described more in detail at a later point in the description. Beginning at the 200° point and extending through the 240° point 60 on the chart, the knife again moves inwardly for a second time to cooperate with the seam setting block, as will be explained hereinafter, and from the 300° point to the 360° point, the knife is retracted by the cam mechanism described to assume a starting position.

- In addition to the mechanism for moving the knife in and out in the manner described, we have also provided a means for transversely oscillating the knife during a 70 part of its cycle of movement. Thus, on the chart represented in Fig. 3 at the left-hand legend noted as "knife cut barrel cam," it will be observed that at the 140° point on the chart the knife is cutting in a direction at right angles to its movement earlier described to produce a 75 shearing action. The travel is for a limited period from

the 140° point to the 170° point during the first part of the shearing movement, and from the 170° point to the 200° point during the return movement. It will be observed that the 140° point and the 200° point are included in the degree values appearing at the second graph line where the knife is at rest. It will also be observed that as soon as the knife has completed its oscillating cycle across and back, it immediately starts its second inward movement.

As an example of one suitable mechanism for producing this oscillating movement of the knife there has been provided a traverse arm 138 which is pivotally supported externally of the frame side 2 on a bracket 140. The forward extremity of the traverse arm is adjustably secured by a bolt 142 received in an elongated slot 144 formed in an extension of the knife holder 112, which projects through the frame side 2 through a suitable opening formed therein, as has been better shown in Fig. 15.

The position of the traverse arm 138 may be further viewed in Fig. 17. In the latter figure it will be seen that the traverse arm 138 has secured at its opposite extremity, and at the under side thereof, a cam follower 146 which is adapted to engage in a barrel cam 148. This cam is fixed on the main cam shaft T at the point where the shaft projects through the frame side 2, all as shown in Fig. 17.

It will be apparent that as the main cam shaft T turns to make a single revolution cycle, as shown in the chart of Fig. 3, the barrel cam 148 with its cam groove shaped to produce the movement indicated will pivot the traverse arm 138 and thus produce the oscillating movement described. Since the knife holder is slidably attached to the arm by reason of the elongated slot 144, the knife blade is, at all times, free to move in and out. The toggle connection operates to permit pivotal movement of the knife blade holder relative to the connecting links 124 without interference.

Cooperating with the cutter member or knife 110, when in an advanced position, is a device for reversely folding intermediate portions of the length of cloth while suspended from the nip of the measuring roll and its idler roll between the vertical guide plates 39 and 82 earlier described. This device is referred to as a former element and is specially constructed to perform several different operations, as has been pointed out above. Thus, with the aid of the knife blade, the former element operates to simultaneously fold and cut two separated folds of material. The former element also serves as an agency for applying adhesive material internally of each of the folded or hem-forming portions of cloth while the cloth is folded about the knife. Finally the former operates to apply adhesive at the base forming sections of the folded material and to locate two thin ribbons extending in spaced relation to the two lines of folding, in each instance, so as to leave substantial tubular portions.

Figs. 24 to 27, inclusive, illustrate in detail the former element which has been generally denoted by the numeral 150 and which comprises an elongated plate extending transversely between the machine sides 2 and 4. The former is held in upper and lower brackets, as 152, shown in Figs. 13 and 15, bolted to the sides 2 and 4. At opposite extremities of the former element 150 are pinned links 154. The inner ends of these links are pivotally secured to cam arms, as 156, also shown in Fig. 13, and fast on the shaft W.

The cam arms 156 are provided with cam followers 158 (Fig. 20) which are adapted to be received in cam grooves 160 formed in the sides of the cams 132, already described, and best shown in Figs. 35 and 36. It is pointed out that the vertical guide plate 80 is of relatively short length so that its lower extremity normally occurs above the top surface of the former element 150, as may be better seen from an inspection of Figs. 4 to 6, inclusive, and the former is thus free to

pass under this member as it moves into engagement with the cloth.

As seen from an inspection of Figs. 24 to 27, inclusive, the plate body comprising the main part of the former element 150 has been formed with two spaced-apart inner dispensing channels 162 which extend inwardly into communication with a front longitudinally extending channel 164, better shown in Fig. 26, and running all the way across the front of the former element. Located adjacent to the channel 164 is a dispensing head 166 which extends along the entire length of the former element 150 and is constructed of the same thickness as shown in Fig. 6, being secured, for example, by bolts threaded into the openings 168 of Fig. 27.

The dispensing head 166 presents a pair of spaced-apart ribs 170 and 172, and at respective upper and lower sides of these ribs are dispensing slots 174 and 176 which communicate with, and are supplied by, adhesive feeder slots 178 and 180. Adhesive material is brought in through inlet pipes 182 and 184, under pressure; passes through the two openings 162; then is forced along the channel 164; passes through the adhesive feeder slots 178 and 180; and finally to the dispensing slots 174 and 176. By arranging the dispensing slots 174 and 176 at the upper and lower sides of two spaced-apart ribs, as described, and by causing the cut to occur between the ribs, the adhesive is applied to the base section of each hem and in a desirably spaced relation to the lines of folding, thus furnishing an excellent control over the application of adhesive.

The movement of the former element 150 has been indicated diagrammatically in a series of steps appearing in Figs. 4 to 8 and on a larger scale in Fig. 9. As illustrated in the latter figure, the separated ribs 170 and 172 move against the length of cloth and force the engaged portions of cloth around the knife blade 110 and through the opening defined in the vertical guide plate 82. The position of the cutting edge of the knife is so chosen that it terminates along a line lying in a vertical plane which passes through the right-hand surface of the guide 82, as viewed in Fig. 9. Therefore, as the former element is moved forwardly into cutting engagement with the knife 110, it will be seen that fiber ends cut by the knife will also lie in this same vertical plane.

Similarly, the dispensing slots 174 and 176 are arranged with an inner edge of each of these slots occurring in the same vertical plane so that ribbons of adhesive material from each former rib may be laid down along lines which are spaced from the lines of folding to produce tubular margins. The ribbons of adhesive also register with the cut ends of the two folds of material. By means of the arrangement described, therefore, adhesive material will be applied on the base section of each of the folds or hems which are being formed so that the cut edges can be pressed in to contact with the adhesive bearing portions of cloth and secured.

Attention is again directed to the chart of Fig. 3, having reference to the movement of the former element noted as the third chart line in this figure. It will be seen that the former element starts its inward movement while the cloth is still feeding and after the knife has begun its inward movement. The former element continues to move toward the knife member after the knife has come to rest and also after the cloth feeding operation has stopped. At a point where the cam shaft T has turned through an arc of 150° , the former element comes to rest and remains stationary while the cam shaft is turning through another arc, stopping at 190° .

It is also pointed out that the knife cut which takes place between the 140° point and the 200° point is largely carried out while the former element is at rest and bearing firmly against the knife in the position shown in Fig. 9, as well as elsewhere in the drawings. Thereafter the former element moves back to its starting position, as shown in Fig. 7, and the knife is retracted, as indi-

11

cated in Fig. 8, thus forming two separate hemmed portions which are adhesively secured together.

Adhesive material may conveniently be held in a container 190 mounted at one side of the machine, as shown in Fig. 12, for example. The adhesive material is maintained under air pressure furnished through an air source 192 with the air pressure being exerted against a plunger 194 adjustably supported within the container 190. A cover 196 is removable for providing access to the interior of the container. At the bottom of the container is a pipe 198 through which adhesive material passes to a valve structure 200. This valve is opened by advancing the lever arm 202 into a forward dotted line position, as shown in Fig. 12, in response to operation of an air cylinder unit 204 connected by conduits 206 and 208 to a solenoid air-operated valve 210. Compressed air is furnished to the air-operated valve through a conduit 212. From the valve 200 in an open position adhesive material is free to pass through another pipe member 214, which is formed with Y portions 216 and 218 which communicate with the two feed inlets 182 and 184 connected into the former element, as shown in Fig. 24.

A switch 220 for controlling the solenoid actuated mechanism is mounted at a convenient point in the machine on a shaft 222, as illustrated in Fig. 14, with the cam fingers being located in the path of travel of actuating cam fingers 224 and 226 adjustably secured on the respective cam 190, as shown in Figs. 31, 32 and 33. The fingers can be set in different positions, as shown in Fig. 33, in spaced-apart relation with respect to one another so that the fingers 224, for example, may first actuate the switch and open the valve 200. After a short interval the fingers 226 will again actuate the switch to close the valve 200. This provides a short period in which adhesive can be delivered through the former element and then abruptly halt it. It will be obvious that the operating interval in which adhesive is forced under pressure against the cloth can be controlled, as desired, by varying the spacings of the fingers with respect to one another, and since the same cam movement controls the feeding of cloth, the adhesive will be delivered in timed relationship, as has been set out in the timing chart of Fig. 3.

Shortly after an application of adhesive has been made in the manner explained above, the former element starts to move away from the folded cloth sections while still wrapped around the knife blade. An important feature here is the holding of the folds of cloth more or less jointly by the knife and the vertically spaced-apart edges of the guide 82. It will be apparent that without these cooperating agencies there might be a tendency for the folds to be retracted with the former element. Such a difficulty is, however, completely obviated by maintaining the knife in the position shown in Figs. 9 and 10.

Almost immediately after the former element is retracted the knife advances inwardly for a second time and through a very short distance, as may be better seen from an inspection of Figs. 3 and 10. The purpose of this second advance movement of the knife is to locate the bevelled cutting edge of the knife beyond a plane passing through the vertical guide 82 to thus ensure that a uniform thickness of blade section extends at all points across the supported portions of folded cloth.

With the cloth thus held and internally supported while in its cut and folded position and while bearing internally applied adhesive material, pressure and heat are applied by two seam setting blocks which engage at top and bottom sides of the folded cloth sections and at points above and below the knife member. These seam setting blocks operate to fuse and set the adhesive material. In the case of the particular adhesive cited in Examples I and II above, a heating interval of from one to ten seconds is found to be satisfactory with the blocks being forced against the cloth to exert the pressure required to accomplish fusing and setting. It may be desired to vary the temperature and pressure conditions

12

noted within rather wide limits either with respect to the particular adhesive cited or in using other types of adhesive materials, or in using sheet materials having different sheet transfer characteristics. It will be obvious that with the knife located between the two folds in the position shown in Fig. 10, it functions as a relatively rigid anvil member against which the seam setting blocks can efficiently operate in timed relationship.

Figs. 28 to 30, inclusive, illustrate in greater detail the construction of the seam setting blocks and Fig. 10 reveals the relative location of the blocks with respect to the guide plate. As shown in these figures, the seam setting blocks include an upper elongated bar member 240 and a lower elongated bar member 242. It will be seen in Fig. 28 that the upper seam setting block 240 is formed with extensions 244 and 246, pivotally attached to which are vertical arms 248 and 250 by means of pins 252 and 254. The upper extremities of the arms 248 and 250 are, in turn, pivotally secured by pins 256 and 258 to lever members 260 and 262, one of which has been better shown in Fig. 29. The levers 260 and 262 are rigidly mounted on a shaft 270 extending between the sides 2 and 4 of the machine frame. Preferably the arms 260 and 262 are secured by draw bolts, as 272, which engage against and lock the shaft 270, as noted in Fig. 29.

Cooperating with the levers 260 and 262 are two other cam levers, better shown in Figs. 15 and 20, and indicated by the numerals 274 and 276. These cam levers are also solidly fixed to the shaft 270 by means of bolts 278, as suggested in Fig. 15. The arms 262 and 274 extend outwardly from two opposite sides of the shaft 270, in the manner indicated in Fig. 14, to comprise a rocker member and, similarly, the arm 260 and the lever 276 comprise a second rocker member on the shaft 270. It will be apparent, therefore, that by actuating this rocker arm mechanism the seam setting block 240 can be reciprocated up and down through a predetermined path of movement. Control of the reciprocating movement has been provided for by securing at the inner extremity of the lever 276 a cam follower 280 which engages in a cam track 284 formed in the side of the cam 132. Similarly, the arm 276 may be provided with a cam follower adapted to engage in a cam track on the cam of opposite hand at the other side of the machine. These cams, as has been earlier explained, are on the main cam shaft and thus provide a complete cycle of raising and lowering the seam setting block during each revolution of the cam.

In the same manner the lower seam setting block 242 is actuated by arms and levers connected on a shaft 290 in a position to comprise a rocker member and indicated by numerals 292 and 294 in Fig. 14. The inner end of the lever 294 is similarly provided with a cam follower 296 which is guided in a cam track 298 formed at the opposite face of cam 132, as shown in Fig. 36.

In moving through their vertical paths of travel the seam setting blocks 240 and 242 are held in sliding engagement with the adjacent surface of the guide plate 82, as is shown in Fig. 10, and to maintain the blocks against the surface of the guide 82, the brackets 114 and 116 may be formed with a shouldered edge which bears against and slidably receives the opposite surfaces of the blocks, as has been indicated in Fig. 14. Thus the blocks are guided at all points in their path of travel.

Referring again to Figs. 28 to 30, inclusive, it will be seen that the lower side of the block 240 has been recessed to provide a relatively narrow rib 298 and, similarly, the block 242 has been recessed at its upper side to provide a relatively narrow rib 300, the latter structure being best shown in Fig. 10. These rib portions are chosen of a size adapted to substantially include and overlie the ribbon of adhesive material which has previously been applied to the folded sections of cloth

through the dispensing slots of the former. It is again pointed out that the inner surfaces of the ribs 298 and 300 occur in register with the cut ends left by the knife as it separates the two folded sections, and since ribbons of adhesive material have also been applied to register with these cut ends, the heating blocks operate to compress the cut ends into the base section of the hem in each instance and to completely embed and lock these cut ends in the respective base sections.

In order to furnish a suitable degree of heat at the 10 time the blocks are pressed down on to the cloth, there has been provided a heating unit 302 which is detachably supported in an opening extending through the seam setting blocks, as shown, and the temperature to which the heating block may be raised is controlled by a thermostat 304, also shown in Figs. 28 and 30. Similar heating means may be provided for the lower seam setting block. In this operation, for example, the temperature of the adhesive may be raised to temperatures of the order of magnitude of from 300° to 400°.

It may be found desirable to accomplish a design-forming operation in conjunction with the setting of the adhesive material, and where this is desired to be carried out the heating blocks may be furnished with inset bars 306, as shown in Fig. 30. Attached through the 15 base of the rib 298, for example, are design-forming needles or other suitable die portions 308 which can be adjustably anchored in the insert 306.

The upper and lower seam setting blocks operate in timed relationship to the other operations described in the manner particularly illustrated, for example, in Fig. 3. It will be observed that at the 140° point on the chart the two seam setting blocks have moved into an intermediate position where they are temporarily held for a short interval. During this interval the adhesive feed 20 operates between the 140° point and the 160° point. At the 190° point on the chart the former element has started to move away and at the same point the seam setting blocks start to move toward one another. These blocks reach a fully operative position at the 220° point and remain in a pressure-applying position throughout an interval included between the 210° point on the chart and the 300° point. Thereafter the cam mechanism operates to return the blocks to a starting position and their cycle of movement is later repeated.

It is pointed out that by means of the arrangement of former knife and seam setting means described, a very sharp and accurate control of the movement of each of these members may be secured in proper sequence necessary to both application and setting of the adhesive. Thus a unique combination of steps are carried out in a very rapid and accurately timed manner.

The tubular type hem which can be produced by the operations outlined has been illustrated in a somewhat enlarged form in Fig. 11 which illustrates diagrammatically a hemmed edge of a diaper having a tubular margin, as shown. It is particularly pointed out that the cut fiber ends are pressed down into the base section of the hem shown in Fig. 11 and are thus protected from accidental displacement. Moreover, the body of adhesive, indicated diagrammatically in the figure, is seen to be more heavily concentrated at the inner portions of the adhesive-bearing cloth sections so that a strong bonding effect is realized and yet very little of the adhesive actually is present at the exposed surfaces of the constituent folded sections. As a result the normal textile characteristics of the hemmed area are left substantially unchanged.

Conveyor mechanism

Directly after the lower seam setting block 242 has moved away from the respective hemmed portion which has been formed and the knife is retracted, it will be obvious that there is left a separate hemmed article which starts to drop downwardly away from the selvage-forming mechanism, as has been suggested diagrammatically 70

in Figs. 7 and 8. This hemmed article has been denoted by the numeral 310.

In accordance with the invention a conveyor mechanism is further provided in the machine to receive the separated hemmed article 310, and parts of this conveyor mechanism are illustrated in Figs. 1, 2 and 37. Included is a multibelt conveyor member 312 which travels over pulley members, as 314 and 316, diagrammatically indicated in Fig. 4. These pulley members are located at different levels to position the conveyor so that it moves along an inclined path suitable for picking up the lower end of the hemmed article 310 to carry it upwardly in the manner suggested in Fig. 4. To achieve this inclined path of travel the pulley 316 may be supported on suitable shaft means 318 mounted between extension brackets, as 320, shown in Fig. 1, in turn fastened at one end of the cloth machine. The lower pulley member, as shown in Fig. 1, may be mounted on a shaft 322 extending between the frame sides and better shown in Fig. 37.

At the outer extremity of the shaft 322, as noted in Fig. 37, is located another pulley member 324 belted to a rearwardly located pulley 326 which is fast on a shaft 328. This shaft is driven by a gear 330 in mesh with another gear 332 on shaft S, all as shown in Fig. 37.

In producing a hemmed article of the character described, it has been found to be desirable for folding and packaging purposes to arrange the hems with the folded portions thereof occurring in an uppermost position as the article is conveyed forwardly. It is pointed out that 30 because of the specific arrangement of the selvage-forming mechanism described above, the hemmed section will invariably be located upon the inclined conveyor member in a reverse position from that sought. Therefore, it may be important to provide means for turning over the hemmed article.

In this connection there has been devised a cloth reversing apparatus particularly shown in the drawings in Figs. 38 and 39. As noted therein, the conveyor 312 conducts the hemmed article 310 to a second conveyor 334, driven by pulleys 336 and 338. Arranged at points just below the pulley 318 is an air jet member 340 connected to a source of compressed air which is operated by a solenoid controlled air valve 342, as shown in Fig. 38. A light source 344 is arranged at one side of the 40 machine and at the opposite side is a photoelectric cell 346 so that as a hemmed article starts to drop down between these two members a switch is actuated for the solenoid air valve control and a series of jets of air are applied against an adjacent side of the cloth article with the result that the uppermost hemmed edge of the article is instantly turned over into a position such as that shown by the dotted line of Fig. 39. Thereafter this turned section of the article falls upon the conveyor 334 and is advanced with both hemmed edges lying in an uppermost position. At this point inspection of the goods 50 may be conveniently carried out, to be followed by suitable folding and packing operations.

The selvage forming mechanism may be employed in a modified form for producing a selvage without the tubular hem construction described. For example, in Figs. 40 to 44, inclusive, we have shown a selvage-forming mechanism which makes use of the same cloth feeding arrangement earlier described and which includes a vertical guide plate 350, together with another guide plate 352 in spaced relation thereto. A length of cloth 354 is fed downwardly between the guides in the manner suggested in Fig. 40. At the right-hand side of the guide 60 350, as shown in Fig. 40 is a movable cutting member 356 which includes a knife blade 358 slidably disposed therein. This mechanism may be operated by a cam arm and cam link mechanism corresponding to that already described.

At the left-hand side of the guide plate 352, and somewhat below this member, is provided an adhesive dispensing unit 360 including a body portion 362 through 75 which adhesive is channeled in the same manner and

employing the same mechanism described in connection with the former element above noted. The dispensing unit is formed with upper and lower edges 364 and 366 which are adapted to engage against correspondingly formed edges 368 and 370 on the cutter member.

In operation the adhesive dispensing unit and the cutter member are brought together by a cam arm mechanism of the type described to engage the length of cloth 354 at two opposite sides thereof, as shown in Fig. 41. Adhesive is then extruded through the dispensing unit and applied in a thin ribbon extending across the cloth, as has been suggested at points denoted by the numeral 372 in Fig. 41. In this latter figure the adhesive dispensing unit and the cutter member have been shown in a retracted position and with a seam setting block 374 moved forwardly and downwardly along a diagonal path represented by the arrow 376 into close proximity to the ribbon of adhesive 372. The heating block is allowed to remain in this position for a very short interval determined by the nature of the adhesive employed and then the seam setting block 374 moves inwardly into spaced relationship with the cloth while simultaneously the knife 358 advances in the remaining portion of the cutter member 356 into a cutting position so that the knife cuts through the adhesively secured parts of cloth in the manner suggested in Fig. 43. There is thus produced a selvage edge, such as 376, shown at the upper part of the cloth item 378 in Fig. 44.

The invention has been described with reference to a single layer or web of cloth fed through the measuring roll and its cooperating idler roll. However, it is intended that in some instances the method and apparatus of the invention may be utilized to handle a plurality of webs or layers of cloth. For example, in Fig. 45 there has been indicated diagrammatically two webs W1 and W2 which are illustrative of feeding into a machine of the character described two webs in parallel spaced-apart relationship. These webs may be handled by separate forming and adhesive applying units chosen such that they will accommodate the respective layers. If desired there may also be employed with such an arrangement a single adhesive dispensing head in which portions may be blanked out to avoid dispensing adhesive at the points of spacing between the separated webs.

Another arrangement for using two or more webs of cloth has also been suggested in Fig. 46 in which the supply roll 10 feeds cloth through the take-off mechanism to the measuring roll 32 and its cooperating idler roll 34 in the manner already described.

Attached in cooperating relationship with this mechanism is a second supply roll of cloth, indicated by the numeral 416, which may, for example, be located above the measuring roll 32 in a position to allow a second length of cloth 418 to be drawn downwardly by means of the rolls 32 and 34 and in contact with the length of cloth 415. It is pointed out that the length of cloth 415 acts as the master layer which holds the layer 14 against itself and draws this layer away from its roll 416 in measured quantities.

It will be apparent that the double layer of cloth may then be treated in any one of the ways indicated above, or joined together at selected points along desired paths by adhesive material. It will also be apparent that the invention, although discussed with reference specifically to the producing of a diaper, is capable of being employed in forming various other types of specialty cloth items, such as bags, sheets, pillow cases, handkerchiefs, flags, curtains, and the like.

While we have shown and described preferred embodiments of our invention, it should be understood that various changes and modifications may be resorted to in keeping with the spirit of the invention as defined in the appended claims.

This application is a continuation-in-part of application Ser. No. 268,372, filed January 26, 1952.

Having thus described our invention, what we desire to claim as new is:

1. A machine of the class described, including roll means for feeding a sheet material, a mechanism for engaging the sheet material and forming a selvage therein, said mechanism including means for applying an adhesive to the material, an apparatus for applying heat and pressure to the adhesive bearing portions of the sheet material, and cutter means for separating adhesively secured portions from one another after the said adhesive has been heated.
2. A machine according to claim 1, in which the mechanism for engaging intermediate portions of the material includes a selvage forming element constructed and arranged to reversely fold the material at two spaced-apart points, and means for adhesively securing the folded portions.
3. A machine according to claim 1, in which the said mechanism includes a selvage former element presenting a plurality of fold-forming ribs arranged in spaced-apart relationship, movable cutter means cooperating with the said ribs for folding the said material around and in between the said ribs and then separating the folded portions, and means for adhesively securing the folded portions.
4. In a cloth hemming machine having means for supporting a length of cloth therein, a selvage forming mechanism including a former element movable into engagement with the length of cloth to support engaged portions thereof in a folded position, dispensing means for distributing an adhesive between the folded portions, and an apparatus for applying heat and pressure to the adhesive bearing portions, and means for cutting the cloth after the adhesive has been heated.
5. In a cloth hemming machine having means for supporting a length of cloth therein, a selvage forming mechanism including a former element movable into engagement with the length of cloth to support engaged portions thereof in a folded position, means for adhesively securing the folded portions at spaced-apart points, and cutter means for separating the said adhesively secured portions.
6. A structure as defined in claim 5, in which the means for adhesively securing the folded portions include an adhesive dispensing structure movable with the said former element, and an adhesive container communicating with the said dispensing structure.
7. A structure as defined in claim 6, including means for exerting pressure on the adhesive in the said container, and valve means for controlling flow of adhesive from the container through the said adhesive dispensing structure.
8. A structure as defined in claim 7, including means for opening and closing the said valve.
9. A structure as defined in claim 8, including cam means for producing oscillating movement of the said cutter means and the said cutter cam being constructed and arranged to operate in timed relationship with respect to the said valve cam such that the dispensing of adhesive occurs simultaneously with oscillation of the cutter.
10. A machine as defined in claim 4, including seam setting blocks for applying heat and pressure to the adhesively secured portions in timed relation to movement of the former element.
11. In a cloth hemming machine having means for supporting a length of cloth therein, a selvage forming mechanism including a former element movable into engagement with the length of cloth to support engaged portions thereof in a folded position, said former element comprising an elongated plate having at one side thereof upper and lower fold-forming ribs occurring in spaced-apart relation, said plate being recessed to provide an adhesive dispensing structure, said structure being provided with dispensing slots occurring at the spaced-apart points along upper and lower sides of the said former ribs,

means for forcing adhesive through the adhesive dispensing slots to secure the folded portions of the cloth, a pair of seam setting blocks arranged to move into engagement with respective upper and lower sides of the said folds of cloth and apply heat and pressure to set the adhesive material, and means for cutting the cloth at points intermediate the upper and lower fold-forming ribs.

12. A machine according to claim 11, including cam means for withdrawing the former element from folded portions of the cloth, and a cam operated mechanism for controlling movement of the seam setting blocks in timed relation such that the blocks move into contact with the folds of cloth after the former element has been withdrawn.

13. In a cloth hemming machine having means for supporting a length of cloth therein, a selvage forming mechanism including a reciprocating former element for engaging at one side of the length of cloth, a movable cutter member cooperating with the former element to fold portions of the cloth about the former element, means for applying adhesive to the folded portions of cloth while engaged by the former and cutter members, means for oscillating the cutter member simultaneously with application of adhesive to the folded portions of cloth, and means for applying heat and pressure between two opposite sides of the folded portions while separated by the cutter member.

14. A structure as defined in claim 13, in which the means for applying heat and pressure includes a pair of seam setting blocks constructed and arranged to move toward one another into contact with the folded portions of the cloth and apply heat and pressure to the said adhesive therein.

15. A structure as defined in claim 14, including cam operated means for controlling movement of the heating blocks in timed relationship with the movement of the cutter member such that pressure and heat are applied after the cutter member has completed its cycle of oscillation.

16. A structure as defined in claim 15, including cam means for retracting the said former element and simultaneously advancing the cutter member just prior to application of pressure and heat by the said seam setting blocks.

17. In a cloth hemming machine having means for periodically feeding a length of cloth, a selvage forming mechanism including a reciprocating former element, said former element being constructed with upper and lower spaced-apart ribs and movable into engagement with the length of cloth to support engaged portions thereof in a reversely folded position, means for adhesively securing the folded portions, cutter means for separating adhesively secured portions of the cloth, said cutter means including a transversely disposed blade, slide members for slidably supporting the blade therein, a cam actuated linkage connected at opposite ends of the blade for moving the blade toward and away from the said former element, and means including a cam roll member operatively connected at one end of the blade for producing oscillating movement of the blade in timed relationship to its travel toward and away from the former.

18. A structure as defined in claim 17, including a pair of vertically disposed spaced-apart guide plates located between the cutter means and the former element in the position assumed by these members at the beginning of a feeding cycle, said guide plates constructed and arranged to receive and guide the said length of cloth between the former element and the cutter means and further being recessed at intermediate portions therein to provide passageways through which the former element and cutter means may pass to engage the cloth while in a freely suspended state.

19. A structure according to claim 18, in which the passageway in one of the guide plates is of a size so chosen as to receive top and bottoms of the former ele-

ment and folded portions of cloth located about the former element when advanced into the said passageway.

20. In a cloth hemming machine having means for periodically feeding a length of cloth from a roll, a selvage forming mechanism including a reciprocating former element, said former element being constructed with upper and lower spaced-apart ribs which are movable into engagement with the length of cloth to support engaged portions thereof in a reversely folded position, means for adhesively securing the folded portions, cutter means for separating adhesively secured portions of the cloth, a pair of vertically disposed spaced-apart guide plates located between the cutter means and the former element in the position assumed by these members at the beginning of a feeding cycle, said guide plates being constructed and arranged to receive and guide the said length of cloth between the former element and the cutter means, and further being recessed at intermediate points therein to provide passageways through which the former element and cutter means may pass to engage the cloth while in a freely suspended state, one of the said passageways being of a size so chosen as to receive the spaced-apart ribs together with portions of cloth folded about the ribs and to releasably hold the folded portions of cloth when the former element is retracted.

21. A cloth hemming machine comprising a frame having spaced-apart sides, a main cam shaft mounted for rotation between the sides, power driven mechanism for actuating said main cam shaft, feed means for periodically feeding a predetermined length of cloth during each revolution of the said main cam shaft, vertically disposed guide means for receiving the length of cloth, a selvage forming mechanism constructed and arranged to engage against two opposite sides of the said length of cloth at intermediate portions therealong and to simultaneously form two separate hemmed edges.

22. A machine according to claim 21, in which the feed means includes a measuring roll and an idler roll adjustably supported in rolling contact with the measuring roll in a position so chosen that the nip point occurs directly above the said vertically disposed guide means.

23. A structure as defined in claim 22, including a clutch responsive to movement of the power driven mechanism for intermittently producing rotation of the said measuring roll.

24. A structure as defined in claim 22, including a cam mechanism mounted on the said main cam shaft, a take-off arm pivotally supported between the sides of the machine at a point between the said roll of cloth and the measuring roll, a linkage operatively connected to the take-off arm and responsive to movement of the said cam mechanism for unwinding cloth from the roll in timed relationship to the operation of the selvage forming mechanism.

25. A structure as defined in claim 24, including a table mounted at the upper side of the machine for receiving cloth leaving the said take-off arm, and tension roll means transversely arranged above the table for straightening the cloth as it passes to the measuring roll.

26. A structure as defined in claim 21, in which the selvage forming mechanism includes a reciprocating former element, a movable cutting member cooperating with the former element to fold cloth therearound and to cut cloth, means in the former element for applying adhesive material, upper and lower seam setting blocks for applying heat and pressure to adhesive bearing folded portions, a cam mechanism comprising a pair of cams mounted on the said cam shaft in spaced-apart relation, and respective cam linkages and cam followers for the former element, the cutting member, and the seam setting blocks operating in a predetermined timed relationship in response to a single rotation of the said cams.

27. A structure as defined in claim 26, including a

container for holding adhesive, conduit means for conducting adhesive from the container to the said former element, valve means for controlling movement of the adhesive under pressure through the said former to folded portions of cloth, a cam member mounted on the said main cam shaft including means operative during each rotation of the said cam to open and close the valve.

28. A structure as defined in claim 27, in which the said feeding means for feeding a predetermined length of cloth includes a take-off arm pivotally mounted between the said sides of the machine, and a linkage controlled by the said valve operating cam for intermittently actuating the said take-off arm.

29. In a cloth hemming machine having means for supporting a length of cloth therein, a selvage forming mechanism including a former element movable into engagement with the length of cloth to support engaged portions thereof in a folded position, means for adhesively securing the folded portions at spaced-apart points, cutter means for separating the said adhesively secured portions, and a conveyor mechanism including a pair of cooperating conveyor members constructed and arranged to receive a separated cloth portion leaving the cutter means and to turn the cloth portion over upon itself into a position in which the adhesively secured folded parts of the cloth lie in an uppermost position.

30. That improved method of hemming a textile material which comprises feeding a length of textile material into a vertically suspended position in which the lower end of the material is freely supported, engaging intermediate portions of the said length of material at two opposite sides thereof and forming two spaced-apart connected folds of material lying one above another, applying separate adhesive bodies between each of the said folds, cutting the material along a line extending between the folds to separate the folds from one another, supporting the separated folds in spaced-apart re-

lation, and simultaneously applying heat and pressure externally of the constituent portions of each fold to impregnate and set the adhesive bodies therein.

31. That improved method of producing a textile article with a hemmed edge, which comprises feeding from a roll of textile material a predetermined length of the said material and arranging the length of material in a vertically suspended position such that the lower end thereof is freely supported, engaging intermediate portions of the said length of material at two opposite sides thereof and reversely folding the material to form an upper fold and a lower fold in spaced relation to the upper fold, applying separate adhesive bodies at the uppermost folded section and the lowermost folded section, respectively, and cutting the material along a line extending between the upper and lower folds to separate these folds from one another, rigidly supporting the separated folds in spaced-apart relation, and simultaneously applying heat and pressure to impregnate and set the adhesive bodies therein.

32. A method as described in claim 31, in which a plurality of lengths of material are simultaneously fed together into the machine.
